(57) **CLAIM**

The ornamental design for a grip for a cylindrical bottle, as shown and described.

DESCRIPTION

FIG. 1 is an isometric view of a grip for a cylindrical bottle, showing my new design;

FIG. 2 is a front elevational view thereof, the rear elevational view being a mirror image;

FIG. 3 is a front elevational view thereof, shown in environmental use;

FIG. 4 is a top plan view thereof, the bottom plan view being a mirror image; and,

FIG. 5 is a right side elevational view thereof, the left side view being a mirror image.

The broken lines in FIG. 3 illustrate environmental subject matter only and form no part of the claimed design.
